UNITED STATES PATENT OFFICE.

JOEL C. WELLS, OF SOUTHBIDGE, MASSACHUSETTS.

OPHTHALMIC MOUNTING.

1,132,754.

Specification of Letters Patent. Patented Mar. 23, 1915.

Application filed May 29, 1914. Serial No. 841,814.

To all whom it may concern:

Be it known that I, JOEL C. WELLS, a citizen of the United States, residing at Southbridge, in the county of Worcester and State 5 of Massachusetts, have invented certain new and useful Improvements in Ophthalmic Mountings, of which the following is a specification.

My invention relates to improvements in 10 ophthalmic mountings and has particular reference to improved means for retaining the same in position on the face of the wearer.

The leading object of my invention is the 15 provision of a novel and improved form of pad or retaining member which will so engage the nose as to resist to a maximum any tilting or rotating movement of the mounting on the face.

20 A further object of my invention is the provision of an improved guard particularly adapted to resist that form of tilting or outward swinging of the glasses which occurs when the wearer is leaning over as to pick 25 up something from the floor or in other unnatural positions.

Other objects and advantages of my improvement should be readily apparent by reference to the following description taken 30 in connection with the accompanying drawings, and it will be understood that I make any modifications in the specific details of construction shown and described within the scope of the appended claims without departing from or exceeding the spirit of my 35 invention.

Figure I represents a front elevation of a mounting embodying my improvement. Fig. II represents a sectional view on the line 40 II—II of Fig. I, illustrating a slightly modified pad. Fig. III represents a semi-diagrammatic side elevation illustrating my mounting in position on the face of the wearer when leaning over. Fig. IV represents a view of a modified construction of 45 my guard used in connection with a spring bridge mounting. Fig. V represents a view of the same applied to an ordinary finger-piece mounting. Fig. VI represents an enlarged sectional view on the line VI—VI of 50 Fig. II, illustrating one form of my upper pad.

In the drawings, in which similar characters of reference are employed to denote corresponding parts throughout the several

views, the numeral 1 denotes the lenses of the mounting connected by the bridge member 2 which may be either of the rigid or spring type as may be preferred, my guard being adapted to operate with either form 60 of bridge.

In that form of my invention illustrated in Figs. I to III inclusive, I have illustrated a type of mounting in which the lower guard or bearing member 3 is rigidly secured to the 65 mounting, while an upper movable arm 4 is employed carrying my improved gripping member. My gripping member in the form here illustrated comprises the basal plate or bearing member 5 having projecting inwardly therefrom the contact members 6 which may be of any desired configuration, either square, round or otherwise as is shown in the different views, and which may be of any desired number, either two, as shown in 70 Fig. II, three, as shown in Fig. IV, or four as shown in Fig. V, it not being my intention to limit myself to any particular number of these points.

In Fig. IV in place of the fixed lower and 80 movable upper bearing members I have shown my guard as consisting of a single piece held in an ordinary stud box 7, and having the rearwardly extending arm 4' carrying the upper anchoring member. 85

Fig. V represents a view quite similar to Fig. IV, with the exception that I have here illustrated what is termed a finger piece mounting in place of a spring bridge mounting, the construction and operation of the 90 guard being similar in all essential respects.

The great advantage of my improvement is probably best apparent by reference to Fig. III, from which it will be seen that when the person is leaning forward toward 95 the floor, for instance, a pull is exerted particularly by the lower portion of the lenses and mounting as at 8, the mounting tending to move in the direction of the arrow 9 off of the face of the wearer, the chief loosening movement being noticeable at the pad 3. In this movement the mounting would normally rotate around the point 10, where the arm 4 engages the upper pad as a center and were my upper pad the usual construction, 100 that is, with a single engaging space, it would have a certain tendency to slide on the face and thus allow of some loosening or downward swinging movement of the mounting. It is to counteract this loosening move- 105 110

ment and securely retain the glasses in position under all conditions that I have provided my improved guard.

It is to be noted that I have shown one of the two members 6 as disposed near the upper and the other near the lower end of the upper bearing member or pad 5. The purpose of this should be readily apparent by reference to Fig. III, from which it will be seen that should the mounting have any tendency to rotate about the point 10 as a center the upper member 6 will engage the nose to resist any swinging movement thereof in the direction of the arrow 11 while the lower member 6 will engage the nose to resist any movement in the direction of the arrow 9, and consequently the mounting will be firmly yet comfortably held in place against any such twisting movement and liability of slipping off of the face is consequently reduced to a minimum. In addition, however, to resisting any loosening movement with the nose in the position shown in Fig. III, my projections 6 will satisfactorily engage the nose when the head is in upright position to resist any forward tilting or sliding movement of the upper portion of the mounting as a whole or any outward twisting thereof, as when the same tends to loosen in the ordinary manner.

From the foregoing description taken in connection with the accompanying drawings the construction of my device should be readily apparent, and it will be seen that the members 6 are extremely efficient under all conditions and are particularly efficient under the peculiar conditions met with when a person is leaning over.

It will be noted moreover that I may make use of either the two points shown in Fig. III, the three points shown in Fig. IV, or the four points shown in Fig. V, in any desired relation to each other, or on any

guard, and thus take care of any swinging on an arc at either two opposed points or at 45 more than two points as may prove necessary according to the particular conditions of service, or the peculiar configuration of the nose to be fitted therewith.

I claim:

1. The combination with a main guard, of a pad therefor comprising a base plate, an attaching member intermediately secured thereto and projecting therefrom, and separate bearing portions carried by the pad 55 near the ends thereof and extending inward to engage the nose and prevent rotative movement.

2. The combination with a lower bearing member, of an arm extending thereabove, a 60 supporting pad carried by the arm, and a contact point carried by the pad and projecting inward therefrom adjacent each corner thereof for engagement with the nose.

3. In an ophthalmic mounting, an upper 65 holding pad for securing the same in position on the face, said pad being of minimum necessary length to prevent tipping outward of the mounting at the top or outward rotation from the bottom, means carried by the 70 mounting and engaging the pad intermediate the ends thereof for connecting the pad and the mounting, the said pad being relieved at the center whereby the end portions only of the pad contact with the face of the 75 wearer for retaining the mounting, the front edges of the contacting portions being substantially straight to resist to a maximum any rotating movement of the pad about its center.

In testimony whereof I affix my signature in presence of two witnesses.

JOEL C. WELLS.
